UNITED STATES PATENT OFFICE.

FRED E. TICHENOR, OF MUKWONAGO, WISCONSIN.

MILK-CAN-LOADING DEVICE.

SPECIFICATION forming part of Letters Patent No. 691,825, dated January 28, 1902.

Application filed June 17, 1901. Serial No. 64,839. (No model.)

To all whom it may concern:

Be it known that I, FRED E. TICHENOR, a citizen of the United States, residing at Mukwonago, in the county of Waukesha and State 5 of Wisconsin, have invented a certain new and useful Improvement in Milk-Can-Loading Devices, of which the following is a specification.

My invention relates to devices for loading milk-cans from the receiving-platform to the 10 car in which they are intended to be conveyed to market.

I have shown my invention as applied to a platform, the parts being arranged in such manner as to effect the desired result; but I 15 do not wish to have it understood that I am limiting myself to the particular form and construction of the several parts shown.

In all countries where milk is handled in cans and sent thus to market it is the common 20 practice to accumulate these cans on a fixed platform as the farmers arrive with their loads, and when the train which is to convey the milk to market arrives it stands upon the track and the cans are lifted or partly 25 thrown from the platform to the car. This naturally necessitates the assistance of several persons, for there can be one or more persons inside the car, one or more outside immediately at the car-door, and one or more 30 back on the platform to bring forward the cans placed farthest from the edge of the platform. Moreover, this operation consumes a good deal of time, and during such time in many countries the car is standing upon the 35 main line, thus preventing its use for other purposes. The milk-trains are proverbially slow because of the delay incidental to this operation. The cans are of necessity very strongly made, yet they are soon injured by 40 this operation, for in working rapidly the heavy cans are thrown or rolled from place to place under conditions which tend to rapidly destroy them.

My invention is illustrated in the accompanying drawings, wherein—

Figure 1 is a plan view of the platform and horizontal section of a car. Fig. 2 is a side elevation. Fig. 3 is a cross-section of an enlarged detail.

Like parts are indicated by the same letter in all the figures.

A A are the timbers which support the plat-

form B. This platform is inclined and connected at its upper end with a horizontal platform C.

D D are a number of chutes on the inclined platform, formed by the rails E E, preferably T-shaped in cross-section. F F are milk-cans, resting each upon two flanges of such T-rails. The chutes are provided where necessary each with an inwardly-curved end G, whereby the several chutes are arranged to discharge their cans toward the center or middle line of the platform.

H H are a series of loops pivoted on stands J and one for each chute.

The chutes are of varying lengths, as indicated, though the precise arrangement of their discharge ends may be varied.

K is a hinged plate pivoted at L to the fixed frame and supported by means of the brackets M and adapted when down to rest on the floor of the car N at the open door O. When this hinged plate is not in use, it is turned upward into the position indicated in dotted lines in Fig. 2, and here it is preferably secured in position, for example, by latches P P.

The use and operation of my invention are as follows: When the hinged plate is turned up into position, (indicated in dotted lines in Fig. 2,) the space along the side of the track is clear and the car may pass freely along such track. Moreover, this hinged plate, if properly secured in this position, effectually 80 prevents the cans from escaping from the platform, even if the securing stop or loop H should happen to be broken or absent from any given chute. Each chute is preferably provided with such stop or closure at its 85 lower end to prevent the escape from it of the cans previously placed in such chute. It would be assumed that the platform is in this position for use, each loop-stop at the end of the chutes in position, and the hinged plate 90 secured in its vertical position when the farmers arriving with their cans put them on the platform C, whence they are put into the 95 chutes D. Each can will slide down on its chute to the end thereof, where it is arrested, and other cans can be in like manner placed in the chute until it is full, each resting upon the can next below it. The inclination of these chutes may be greatly varied and the

ordinary means for causing the cans to freely slide down the chutes may be adopted, such as various bearings or rollers or the like and lubricating material; but my invention is distinguished in the inclined chute, for the inclination can be such as to cause the cans to act as indicated without any additional aids. When the car has arrived, it will stop, as heretofore, opposite the platform, the door will be thrown open, and the car-men will unload and drop the hinged plate into the position indicated in the drawings. The car-men can now step out onto the platform and open some one of the chutes, whereupon the cans in that chute will slide down, free themselves from the chute, and pass into the car across the inclined hinged plate on the middle line thereof. This action could be kept up until all of the cans are in the car, the chutes being closed as fast as they are emptied. Very little effort will be required to start the cans, and once started the momentum of the line of cans will be sufficient to carry them all down into the car.

As previously suggested, the form and construction of these several parts could be greatly altered without departing from the spirit of my invention and many minor details could be added or omitted without affecting the principal claims.

I claim—

1. In a device for loading milk-cans the combination of a suitable supporting-platform with a series of inclined chutes formed each of inverted-T beams and provided with inwardly inclined or curved ends where necessary so as to cause all of said chutes to discharge toward the line of the middle chute, a stop at the end of each chute and a hinged platform adapted, when in its vertical position, to serve as the stop below all the chutes and when depressed to serve as a continuation of the inclined platform below the chutes.
2. In a device for loading milk-cans into railway-cars the combination of a series of inclined chutes, with an open inclined platform at the lower end thereof, said chutes opening onto said platform so as to discharge the cans toward the middle thereof, each chute having a free discharge-opening, and a movable part of said platform which bridges the distance between the fixed portion and the car.
3. In a device for loading milk-cans the combination of a series of chutes along which the cans move toward the car, some of said chutes having inwardly-turned ends, and an

open platform-space below and about the ends of said chutes, so that each can freely discharge upon the same and stops one for each chute to hold the cans in the same.

60

4. In a device for loading milk-cans the combination of a series of chutes along which the cans move toward the car, some of said chutes having inwardly-turned ends, and an open platform-space below and about the ends of said chutes, so that each can freely discharge upon the same, and a movable platform portion adapted to bridge the space between the fixed platform of the car and when turned into its vertical position to serve as a stop for the chutes.

65

5. In a device for loading milk-cans the combination of a series of inclined chutes each adapted to hold a row of cans, with inwardly-turned lower ends for certain chutes, and an inclined platform having an outer guard so that each of said chutes has a free delivery-way for its cans to the middle line of said chutes.

70

6. In a device for loading milk-cans the combination of a series of inclined chutes each adapted to hold a row of cans, with inwardly-turned lower ends for certain chutes, and an inclined platform having an outer guard so that each of said chutes has a free delivery-way for its cans to the middle line of said chutes, the lower portion of said platform being hinged.

80

7. In a device for loading milk-cans the combination of a series of inclined chutes each adapted to hold a row of cans, with inwardly-turned lower ends for certain chutes, and an inclined platform having an outer guard so that each of said chutes has a free delivery-way for its cans to the middle line of said chutes, and a separate stop for the discharge end of each chute.

85

8. In a device for loading milk-cans the combination of a series of inclined chutes each adapted to hold a row of cans, with inwardly-turned lower ends for certain chutes, and an inclined platform having an outer guard so that each of said chutes has a free delivery-way for its cans to the middle line of said chutes, and a separate stop for the discharge end of each chute, and the lower portion of said platform hinged.
